CLAIM

The ornamental design for a fastener for pegboard, as shown and described herein.

DESCRIPTION

FIG. 1 is a perspective view of a fastener for pegboard showing the claimed design.

FIG. 2 is a front view thereof.

FIG. 3 is a rear side view thereof.

FIG. 4 is a left side view thereof.

FIG. 5 is a right side view thereof.

FIG. 6 is a top plan view thereof.

FIG. 7 is a bottom plan view thereof.

FIG. 8 is a front view thereof showing the fastener for pegboard in a state of use; and,

FIG. 9 is a cross-sectional view taken along a line 9-9 of FIG. 8 showing the fastener for pegboard in a state of use. The broken lines are used to illustrate environmental structure and form no part of the claimed design.

1 Claim, 9 Drawing Sheets
